FLAME HEATING APPARATUS

James O. Bishop, Torrance, and Lloyd L. Babcock, Compton, Calif., assignors to The National Supply Company, Pittsburgh, Pa., a corporation of Pennsylvania

Original application August 3, 1940, Serial No. 350,196. Divided and this application March 6, 1943, Serial No. 478,256

5 Claims. (Cl. 158—27.4)

1

This invention relates to flame hardening apparatus and more particularly to the torches thereof and to the provision of means for avoiding the overheating of the same.

This application is a division of our copending application, Serial No. 350,196, filed August 3, 1940, for Flame hardening method and apparatus, now Patent No. 2,321,645, granted June 15, 1943.

It is an object of this invention to provide a flame hardening or heating apparatus wherein means are provided to prevent the accidental over-heating of the apparatus by preventing flow of combustible heating gas until circulation of a cooling medium is established.

Another object of this invention is to provide a flame heating or hardening apparatus including a torch or torches through which a combustible mixture of gases is dispersed and through which means are provided for maintaining a circulation of a cooling fluid and where means are provided responsive to the pressure of the cooling fluid for admitting combustible gases to the torch or torches.

Other objects and advantages of this invention it is believed will be apparent from the following detailed description of a preferred embodiment thereof as illustrated in the accompanying drawing.

In the drawing:

Figure 1 is a sectional elevation of one of the torches embodied in our invention.

Figure 2 is a sectional end view taken substantially on the line 2—2 of Figure 1 illustrating two such torches in position with relation to an element to be flame hardened or heated.

Figure 3 is a diagrammatic elevation partly in vertical section of the flame heating apparatus embodied in our invention.

Figure 4 is a sectional view of the combustible gas control valve utilized in our invention illustrating the valve in closed position.

Figure 5 is a sectional view of the valve in open position.

In the preferred embodiment of our invention illustrated in the accompanying drawing, 1 and 2 indicate torches which are utilized for directing a flame against the surface of an element 3 which is to be flame hardened or heated. The two torches are alike except being formed as right- and left-handed so that the construction of only one such torch need be described.

The torch 1 has a broad flat side 4 in which there is formed a large number of orifices or burner openings 5 for the distribution of the

2

flame over the surface of the work 3. The orifices 5 are fed combustible gas through a plurality of parallel lateral feed passages 6 which extend from a main feeder passage 7 which extends longitudinally through the torch. The passage 7 at the end of the torch is connected with a conduit 8 through which a suitable combustible gas mixture is supplied from any suitable source. Each of the flame orifices 5 is formed on the face of the torch 1 with a counterbore 5a.

Between the flame orifices 5 in the body of the torch 1 there are provided a multiplicity of air ports 9 which extend through the body of the torch and through which air passes from the back of the torch to the face to maintain an abundance of air for completing the combustion of the gases.

Formed through the torch 1 is a cooling passage 10 which is connected by means of a transverse passage 11, and a second longitudinally extending cooling passage 12, the end of which communicates with the transverse passage 13 which is in communication with the discharge passage 14. The cooling passage 10 is connected in communication with the inlet pipe 15 while the discharge passage 14 is connected in communication with a discharge pipe 16. The passages thus provide for the distribution and circulation of a cooling fluid or coolant such as water through the torch.

Means are provided for permitting the admission of combustible gas to the torches when the pressure of the coolant attains a desired pressure. This provision acts as a safety device to prevent inadvertent overheating of the torches 1 and 2.

The particular form of means illustrated in the drawing for accomplishing this result is: The gas which may have been suitably mixed with air or oxygen passes through a meter 17 and from the meter 17 passes through a conduit 18 in which there is mounted a valve 19. After passing the valve 19, the gas passes into a flow governor indicated at 20 from which the gas passes through a conduit 21 to a suitable mixing valve not shown and from which mixing valve the gas passes to the conduit 8.

The valve 19 is of the sliding sleeve type and includes a sleeve 22 which slides along the pipe section 23. Positioned in the pipe section 23 is a dam or blind 24 which obstructs the flow of fluid through the pipe. On opposite sides of the dam 24 are ports 25 and 26. The sleeve 22 has spaced packing 27 and 28 on opposite sides of an annular recess 29. There is also secured to the sleeve 22 a shifter 22a for shifting the sleeve 22

along the pipe 23. As illustrated in Figure 4, the sleeve is moved to the closed position to obstruct flow of the combustible gas. In Figure 5 the sleeve is moved to the position where flow of gas is permitted around the dam 24 through the ports 26 and in a recess 29 and ports 25 back into the pipe 23. Means are provided for maintaining the valve sleeve 22 in the closed position when the pressure of coolant or cooling medium does not meet the desired level to prevent the torches 1 and 2 from overheating. The means as herein illustrated for accomplishing this object are a diaphragm housing 30 in which a flexible diaphragm 31 is mounted. The housing 30 is connected through a pipe 32 with the coolant or water supply pipe 33 leading to the intake pipe 15.

Secured to the diaphragm 31 is an operating rod 34 on the end of which there is secured an abutment or interference lug 35 adapted to move into and out of position to prevent the movement of the valve sleeve 22 to the open position. When pressure is exerted against the diaphragm 31, the interference lug 35 is moved out of the path of the sleeve 22 permitting the valve to be opened. When insufficient pressure is exerted against the diaphragm 31, the interference lug 35 prevents opening of the valve 19, thereby preventing the flow of combustible gas to torches 1 and 2. If for any reason the water pressure and water supply line 33 is too low to maintain adequate cooling of the torches 1 and 2, the interference lug 35 will not be moved out of position.

Having fully described our invention and a specific embodiment thereof, it is to be understood that our invention is not limited to the precise details of construction herein set forth, but is of the full scope of the appended claims.

We claim:

1. In a device of the class described, the combination of a torch having a first passageway for combustible gas and a second passageway for the circulation of a coolant, means including a valve for selectively admitting combustible gas to said first passageway, means for actuating the valve to open position, a conduit for delivering a coolant under pressure to said second passageway, and means including a diaphragm actuated by pressure in said conduit adapted to hold the valve actuating means from operation of the valve toward open position until the pressure in said conduit reaches a predetermined value.

2. In a device of the class described, the combination of a torch having a plurality of burner openings, a combustible gas passageway formed within the torch and communicating with the burner openings, means including a valve for se-

lectively admitting combustible gas to said passageway, means for actuating the valve to open position, a second passageway formed in the torch, means to pass a coolant through the second passageway, and means automatically responsive to the pressure of the coolant adapted to hold the valve actuating means from operation of the valve to open position, said automatic means being operatively ineffective to move said valve when the valve is in open position.

3. In a device for flame hardening, the combination of a torch having a first passageway for combustible gas and a second passageway for a coolant, means including a valve for selectively admitting combustible gas to said first passageway, means for actuating the valve, a conduit for delivering a coolant under pressure to said second passageway, and means responsive to the pressure in said conduit adapted to hold the valve actuating means from actuation of the valve toward open position until the pressure in the conduit reaches a predetermined value.

4. In a device for flame treating a metallic surface, the combination of a torch having a plurality of burner openings adapted to lie adjacent a surface to be heated, a passageway for combustible gas formed in the torch and communicating with the burner openings, means including a valve for selectively admitting combustible gas to said passageway, means for actuating the valve, cooling means adapted to prevent overheating of the torch including a second passageway formed in the torch, means to pass a coolant through the second passageway, and means automatically responsive to the pressure of the coolant adapted to hold the valve actuating means from operation of the valve to open position, said automatic means being operatively ineffective to move said valve when the valve is in open position.

5. In a device for flame treating a metallic surface, the combination of a torch having a plurality of burner openings, a passageway for combustible gas formed in the torch and communicating with the burner openings, means including a valve for selectively admitting combustible gas to said passageway, means for actuating the valve, cooling means adapted to prevent overheating of the torch including a second passageway formed in the torch, a conduit for delivering fluid under pressure to the second passageway, and means responsive to the pressure in said conduit adapted to hold the valve actuating means from actuation of the valve toward open position.
